SEALING CLOSURE

Carroll P. Krupp, Akron, Ohio, assignor to The
B. F. Goodrich Company, New York, N. Y., a
corporation of New York

Application March 4, 1943, Serial No. 477,970

13 Claims. (Cl. 2—96)

This invention relates to sealing closures and is especially useful for closing and sealing adjacent margins that are flexible, for example, margins of inflatable suits for aviators.

The principal objects of the invention are to provide for closing and sealing adjacent margins effectively, to provide for maintaining sealing of flexible margins during their flexure, and to provide for simplicity of construction and effectiveness of operation.

Other objects are to provide means for lip-action sealing of adjacent margins, and to provide means for closing and sealing adjacent double-faced margins at their respective faces.

Further objects are to provide an improved sealing closure for detachably uniting adjacent margins, to provide means for sealing effectively the end of the closure, and to provide for sealing of the closure during bending, inwardly or outwardly of the margins and even to a large extent during twisting of the margins.

These and other objects and advantages will be apparent from the following description and the accompanying drawings illustrating embodiments of the invention.

In the accompanying drawings, which form a part of this specification, and in which like numerals are employed to designate like parts throughout the same,

Fig. 1 is a fragmentary perspective view of a sealing closure constructed in accordance with and embodying the invention, parts being broken away and in section.

Fig. 1A is a sectional view showing the closing elements of Fig. 1 in a disengaged condition.

Figs. 2 and 4 are views like Fig. 1 showing, respectively, modified construction of the sealing closure.

Fig. 3 is a sectional view taken along line 3—3 of Fig. 2.

Fig. 5 is a view like Fig. 1 showing a further modification.

Fig. 6 is a plan view of the sealing closure of Fig. 1 applied at an opening in the wall of a body, parts being broken away.

Fig. 7 is a sectional view taken along line 7—7 of Fig. 6.

Fig. 8 is a sectional view taken along line 8—8 of Fig. 6.

Fig. 9 is a plan view of a separable end arrangement of the sealing closure shown in Fig. 1 and including a clamping structure for sealing the end.

Fig. 10 is a sectional view taken along line 10—10 of Fig. 9.

Fig. 11 is a sectional view like Fig. 10 showing an alternate construction when the closing elements are arranged as shown in Fig. 6.

Fig. 12 is a plan view of a closed end arrangement of the sealing closure shown in Fig. 2 and including a clamping structure for sealing the end.

Fig. 13 is a sectional view taken along line 13—13 of Fig. 12.

Fig. 14 is a sectional view taken along line 14—14 of Fig. 12.

Fig. 15 is a view like Fig. 12 showing a modified construction of the end sealing arrangement.

Fig. 16 is a sectional view taken along line 16—16 of Fig. 15, and

Fig. 17 is a sectional view taken along line 17—17 of Fig. 15.

The construction of Figs. 1 and 1A includes adjacent margins 30 and 31, and a pair of closing elements 32 and 33 disposed at the margins in an overlapping relation to one another. One of the closing elements 33 has a flexible marginal portion 34 tapering to an edge 35 for sealing by lip-action of the edge in contact with a sealing surface 36 on the other element 32. Fastener means, such, for example, as a slide fastener 37 and runner 38 arrangement may, if desired, be provided for detachably uniting the margins 30 and 31.

For some applications such, for example, as inflatable suits for aviators, wearing apparel, tents, and other like articles, a preferred form of the invention, as illustrated in Fig. 1, includes the adjacent margins 30 and 31 of woven fabric or other suitable flexible material and the pair of closing elements 32 and 33 of resilient rubber or other rubber-like material or other suitable flexible material disposed at a face of the respective margins in an overlapping relation to one another. Slide fastener elements 37a and 37b are secured, desirably, at the opposing edges of the margins 30 and 31 for co-acting with each other and with a runner 38 to unite detachably the margins and thereby position the closing elements in an overlapping and sealing relation.

The closing elements may be secured to the respective margins by rubber cement or other suitable adhesive material or by other suitable fastening means. Preferably, these elements 32 and 33 are molded and vulcanized integrally with the margins 30 and 31, as shown especially in Fig. 1A, the faces of the margins having a thin coating 30a and 30b, 31a and 31b of rubber for preventing leakage of fluid, such as air or water, therethrough and for facilitating adhering the margins to articles having walls of woven fabric,

for example, coated or impregnated with rubber. As shown especially in Fig. 1A, each closing element 32, 33 comprises a base portion 32a, 33a at a face of one of the margins 30, 31 and a laterally depending portion 32b, 33b terminating in a resilient marginal portion 34, 39 tapering to an edge 35, 40. The parts are constructed and arranged, as by vulcanizing the parts 32 and 33 to the shape shown in full lines in Fig. 1A, so that during engagement of the margins 30 and 31 the resilient marginal portions are in an overlapping relation and the edge 35 of the element 33 is held pressed in sliding contact with the sealing surface 36 on the element 32 for providing a seal by lip-action of the edge 35 by virtue of resilient flexure of the marginal portion 34 of the element 33, as shown by broken lines in Fig. 1A, while opposing areas 36a and 41 on the respective elements 32 and 33 adjacent the edge 35 are maintained in spaced-apart relation so that the lip-action of the edge will not be interfered with by engagement of adjacent surfaces. It has been found that the pressing and sliding action of the edge 35 against the sealing surface 36 is maintained during bending, inwardly or outwardly, of the margins 30, 31 and even to a large extent during twisting of these margins.

The sealing closure described hereinabove is shown in Fig. 6, in which embodiment it may be used for closing adjacent margins 45 and 46 of an opening in the wall of an article, such, for example, as an inflatable suit for aviators. The wall of the suit is made, desirably, of flexible, substantially impervious material like woven fabric coated or impregnated with rubber or other rubber-like material. The margins 30 and 31 of the closure are secured to the exterior face of the wall of the suit at the respective margins 45 and 46 by a suitable adhesive such as rubber cement, or by sewing, or both, and are disposed such that the closing elements 32, 33 extend through the opening to the interior of the suit in the manner shown especially in Fig. 7. A covering and reinforcing strip 47 of rubber-coated fabric, for example, is superimposed on the margins 30 and 31 and secured thereto and to the wall by a suitable adhesive material, or by sewing, or both, thus providing further sealing of the margins 30 and 31, 45 and 46 against leakage of fluid from within the suit. The strip 47 also seals the ends of the margins 30 and 31, as shown in Fig. 6.

The base portion 32a, 33a of the closing elements at the respective ends of the margins 30 and 31 may be provided with a reinforcing shoulder portion 32c, 33c tapered in cross-section for facilitating sealing the end portions of the closing elements, especially at the interior of the suit. The closing elements at the opposing areas 36a and 41 of the marginal portions 35 and 39 are secured together at the ends of the sealing closure by means of a suitable adhesive material, and a covering strip 48 of woven fabric coated or impregnated with rubber or other rubber-like material is superimposed at the interior face of the wall upon the closing elements in the manner shown especially in Figs. 6 and 8, and is adhered in place by rubber cement, for example. Thus the ends of the sealing closure are sealed at the respective exterior and interior faces of the wall of the inflatable suit. The closure arrangement is united, desirably, into an integral structure by vulcanization.

In the operation of the sealing closure, the wearer of the suit engages the margins 30, 31 including the slide fastener 37 by moving the runner

38 at the exterior face of the wall in the direction indicated by the arrow 49 shown in Fig. 6. Coincident with the engagement of the margins and the slide fastener, the closing elements 32 and 33 are drawn together into an overlapping relation at the marginal portions 34 and 39, the edge 35 sliding in contact with and along the sealing surface 36 and resiliently pressing against the surface 36 for providing a seal therewith while the opposing areas 36a and 41 of the elements 32, 33 adjacent the edge 35 are maintained in spaced-apart relation.

The closing elements 32, 33 are capable inherently of closing and sealing effectively the opening in the wall of the inflatable suit initially by virtue of their construction and arrangement providing initial resilient pressure of the lip against the sealing surface and the maintenance of the seal by lip-action of the edge 35 of the resilient marginal portion 34 in sliding contact with the sealing surface 36 is assisted by the action of the dominant pressure within the suit upon the closing element 33 tending to hold the edge 35 against the sealing surface 36 despite bending, inwardly or outwardly, and even to a large extent during twisting of the adjacent margins 45, 46 of the opening in the wall of the suit.

Fig. 9 illustrates an arrangement for the use of the sealing closure as shown in Figs. 1 and 1A for closing and sealing the margins 50, 51 of an opening in the wall of an article, such, for example, as a tent or wading boot or suit, having under some conditions dominant fluid pressure at the exterior face of the wall, in which construction another form of seal for the end of the opening is provided. In Fig. 9 the opening extends at one end to the edge 52 of the free marginal portion 53 of the wall for permitting extensive separation of the margins 50, 51 thereby facilitating, for example, the entrance and exit to and from the tent or facilitating the donning of the boot or garment, while the other end of the opening may be closed substantially as illustrated in Fig. 6.

The margins 30 and 31 are secured at the interior face of the respective margins 50 and 51 by a suitable adhesive, or by sewing, or both, and are disposed such that the closing elements 32 and 33 extend through the opening to the exterior face of the wall. For convenience of operating the sealing closure from the exterior face of the wall, the runner 38 has a projecting element 38a extending outwardly between the resilient marginal portions 34, 39 of the closing elements 32, 33 for mounting a pull-tab 38b, as shown especially in Fig. 10. A covering and reinforcing strip 54 of rubber-coated fabric, for example, is superimposed on the margins 30 and 31, and secured thereto and to the interior face of the wall by a suitable adhesive, or by sewing, or both, thus providing further sealing of the margins 30, 31 against leakage of fluid.

The end of the sealing closure arrangement at the region of the margin 53 of the wall is sealed, preferably, by a clamping structure 55 of stiff material such, for example, as steel or plastic material, and including a backing plate 56 at the interior face of the wall and a pivoting bracket support 57 at the exterior face of the wall for mounting an adjustable clamping member 58 for engaging the closing elements 32, 33. A base portion 57a of the bracket support 57 and the backing plate 56 are secured to the respective faces of the wall at the margin 51 by a pair of spaced-apart rivets 59 extending

through apertures in the margins 34 and 31 and the covering strip 54 and by a suitable adhesive. A bracket element 57b is pivotally mounted on a rivet 60 in a depending leg 57c of the base portion 57a, the bracket element 57b having a threaded aperture in a laterally extending portion 57d for engaging an adjusting screw 58a rotatively secured to a clamping element 58b, as shown in Fig. 10. The adjusting screw 58a has a knurled head 58c for convenience of adjusting the clamping element 58b.

The clamping element 58b has depending sidewalls 58d and 58e for supporting the base portions 32a and 33a of the closing elements 32 and 33, and has a depending margin 58f and 58g of suitable shape at each end for pressing against the resilient marginal portions 34 and 39 of the closing elements to provide a sealing contact at their opposed areas 36a and 41. The clamping element 58b encloses the runner 38 and the pull-tab 38b in the space between the sidewalls and the depending margins.

In the operation of closing and sealing the end of the closure arrangement shown in Fig. 9, the clamping element 58b is disposed in a retracted position adjacent the laterally extending portion of the bracket element 57b, and the bracket element including the adjustable clamping member 58 is pivoted from the upright position shown in Fig. 10 to a position extending along the wall for permitting passage of the runner 38 while engaging the slide fastener 37. Upon engagement of the slide fastener, the bracket element 57b is swung back to the upright position and the clamping element 58b is positioned in contact with the closing elements 32 and 33 by turning the adjusting screw 58a.

The clamping element 58b encloses the runner 38 including the pull-tab 38b and although the seal by lip-action is broken at the portion 38a of the runner, the edge 35 of the closing element 33 contacts the sealing surface 36 of the closing element 32 at the respective ends of the clamping element by virtue of the resiliency of the marginal portions 34 and 39. The depending margins 58f and 58g at the ends of the clamping element press the opposed areas of the resilient marginal portions 34 and 39 together and against the slide fastener elements 37a and 37b which are supported by the backing plate 57, thereby sealing effectively the end of the sealing closure at the region of the marginal portion 53 of the wall.

Fig. 11 illustrates an alternative construction for the clamping structure when the closing elements are positioned at the other or interior face of the wall. The margins 30 and 31 of the sealing closure are secured adhesively at the exterior face of the margins 50 and 51 of the opening in the wall and a covering strip 64 superimposed thereon. A backing plate 66 at the interior face of the wall and pivoting bracket support 57 at the exterior face of the wall are united by the spaced-apart rivets 59. An adjustable clamping member 68 for pressing the slide fastener and runner against the closing elements includes an adjusting screw 68a engaging the bracket element 57b. The screw 68a is rotatively secured to a pressing element 68b which engages the runner 38. The backing plate 66 has a grooved portion 66a for providing backing support for the closing elements 32 and 33.

In the operation of the clamping structure shown in Fig. 11, the slide fastener 37 is engaged after the bracket element 57b and the adjustable

clamping member 68 which is in a retracted position, have been pivoted from the upright position about the rivet 60. Upon engagement of the slide fastener, the bracket support 57b including the member 68 is swung back to the upright position. The adjusting screw 68a is manipulated to contact the pressing element 68b with the runner 38 and to press the runner against the closing elements until the opposing areas 36a and 41 of the marginal portions 34 and 39 are in abutting relation. Thus the end of the closure is sealed effectively against the leakage of fluid.

The modified construction shown in Figs. 2 and 3 is especially suitable for closing adjacent 15 double-faced margins at an opening in the wall of an article, where the wall is under fluid pressure at both faces and may have dominant pressure existing alternately at the respective faces, i. e., a partition in a fluid container. Adjacent double-faced margins 70 and 71 of woven fabric or other suitable flexible material have disposed at one of the faces a pair of elements 72 and 73 of resilient rubber or other rubber-like material for closing the margins 70 and 71 by an overlapping relation of the elements 72 and 73, and have disposed at the other face a second pair of elements 74 and 75 of resilient rubber or other rubber-like material for closing similarly the margins 70 and 71. One element 73, 75 of each pair has a marginal portion 76, 77 tapering to an edge 78, 79 for contacting a sealing surface 80, 81 on the other element 72, 74 in sealing relation therewith by lip-action of the edge 78, 79. Slide fastener elements 82a and 82b are secured, desirably, at the opposing edges of the margins 70 and 71 for co-acting with each other and with a runner 83 to unite detachably the margins and thereby 20 position the respective pairs of closing elements 72 and 73, 74 and 75 in an overlapping and sealing relation.

Preferably, each pair of elements 72 and 73, 74 and 75 are molded and vulcanized integrally with the margins 70 and 71 and are constructed and arranged at the respective faces of the margins in a manner like that described hereinabove for the closing elements 32 and 33 of the construction illustrated in Figs. 1 and 1A. During engagement of the margins 70 and 71 the respective 25 pairs of elements 72 and 73, 74 and 75 close the margins by an overlapping relation of the elements while the respective edges 78 and 79 of the elements 73 and 75 are held pressed resiliently in sliding contact with the respective sealing surfaces 80 and 81 on the elements 72 and 73 for providing a seal by lip-action of the edges 78 and 79 by virtue of the resilient flexure of the marginal portions 77 and 76 while opposing areas on the respective pairs of elements 72 and 73, 74 and 75 adjacent the edges 78 and 79 are maintained in spaced-apart relation, so that the lip-action of the edges will not be interfered with by engagement of adjacent surfaces. Tests have shown that the pressing and sliding action of the edges 78 and 79 against the sealing surfaces 80 and 81 is maintained during bending, inwardly or outwardly, of the margins 70 and 71 and even to a large extent during twisting of these margins. The margins have, desirably, a thin coating 30 70a and 70b, 71a and 71b of rubber or other rubber-like material for preventing leakage of fluid, such as air and water, therethrough and for facilitating adhering the margins to articles having walls of woven fabric, for example, coated or impregnated with rubber or other rubber-like

material. Thus the sealing closure shown in Figs. 2 and 3 provides an effective seal at the two faces of the margins.

For convenience and ease of operation of the sealing closure, the runner 83 engaging the slide fastener elements 82a and 82b has a depending portion 83a for engaging a pull-tab 83b positioned exteriorly of the closing elements at a face of the margins, as shown especially in Fig. 3. The depending portion 83a is arranged at a side of the runner 83 such that it extends through the space between the opposed areas of the marginal portions of the closing elements in a manner providing for minimum breakage of the lip seal and for minimum effort in sliding the runner 83 along the slide fastener.

The modified closure construction including end sealing means as shown in Fig. 12 is applied, for example, to a flexible partition 85 in a compartmented container for fluids, such as water, air, and other liquids and gases. Desirably, the partition 85, which may be of woven fabric coated or impregnated with rubber or other rubber-like material although not necessarily limited thereto, has the sealing closure at an opening for permitting the inspecting and cleaning, for example, of the respective compartments, or even the passing of a workman therethrough.

The margins 70 and 71 of the closure are secured by a suitable adhesive material, or by sewing, or both, to a face of the adjacent margins 85a and 85b of the opening, the closing elements 72 to 75 being disposed at the opening as shown especially in Fig. 14. A covering and reinforcing strip 86 of flexible material such, for example, as woven fabric coated or impregnated with rubber or other rubber-like material is superimposed on and adhered as by rubber cement to the margins 70 and 71 and to the partition 85 for further sealing of the margins 70 and 71.

The ends of the margins 70 and 71 and the closing elements 72 to 75 are sealed at the respective faces of the partition by a pair of covering elements 87 and 88 of flexible material such, for example, as woven fabric coated or impregnated with rubber or other rubber-like material, as shown in Fig. 13. The end portions of the respective pairs of closing elements 72 and 73, 74 and 75 are adhered together by a suitable adhesive material at their overlapping and opposed areas at the region of the covering strips 87 and 88. The arrangement may be united integrally by molding and vulcanization.

A clamping structure 89 at the end of the sealing closure adjacent the covering strips 87 and 88 provides additional sealing of the end for preventing leakage of fluid. The clamping structure 89 of stiff material such, for example, as steel or plastic material, includes a backing plate 90 at a face of the partition 85 and a pivoting bracket support assembly 91, 92 at the other face of the partition for mounting an adjustable clamping member 93 for engaging the closing elements 74 and 75. Base portions 91a of the bracket support and the backing plate 90 are secured, preferably, to the respective faces of the partition at the adjacent margins 85a and 85b by spaced-apart rivets 95 extending through apertures in the margins 70, 71, 85a and 85b and the covering and reinforcing strip 86 and by a suitable adhesive material. A channel element 92 of the bracket support assembly is pivotally mounted on depending legs 91b of the base portions 91a by rivets 95 and 96, the channel element 92 having a threaded aperture in a laterally extending portion 92a for

engaging an adjusting screw 93a rotatively secured to a clamping element 93b, as shown in Fig. 14. The adjusting screw 93a has a knurled head 93c for conveniently adjusting the clamping element 93b. The clamping element 93b is like the clamping element 58b, and accommodates similarly the runner 83 including the portion 83a and the pull-tab 83b and engages in a similar manner the closing elements 74 and 75.

The operation of closing and sealing the end of the closure arrangement shown in Fig. 12 is substantially like that described for Fig. 9. The channel element 92 pivots on the rivets 95 and 96 for swinging the clamping member 93 out of the upright position prior to engagement of the slide fastener 82a and 82b and for subsequently returning the member 93 to the upright position for engaging the closing elements 74 and 75. Adjusting the screw 93a of the clamping member 93 disposes the clamping element 93b for pressing together the opposed areas of the resilient marginal portions of the closing elements 72 and 73, 74 and 75 at the respective ends 93d and 93e of the clamping element 93b and against the slide fastener elements 82a and 82b while also pressing the closing elements 72 and 73 against the backing plate 90 in sealing relation therewith. The runner 83 including the pull-tab 83b is enclosed within the clamping element 93b. An effective end seal of the closure is thus provided.

An alternative end sealing arrangement illustrated in Figs. 15 to 19 includes the sealing closure shown in Figs. 2 and 3 similarly secured at the margins 85a and 85b of the opening in the partition 85, the covering and reinforcing strip 86, a pair of covering strips 100 and 101 at the respective faces of the partition, and a clamping structure 102 for sealing at the ends of the closing elements 72 to 75. The covering strips 100, 101 of flexible material such as woven fabric coated or impregnated with rubber or other rubber-like material are secured to the end of the sealing closure and to the partition by a suitable adhesive material, or by sewing, or both, as shown especially in Figs. 15 and 16, for closing the end of the closure and preventing leakage of fluid therefrom. At the region 103 of these covering strips 100, 101 the respective pairs of closing elements 72 and 73, 74 and 75 are adhered together by a suitable adhesive material at the opposing areas of the marginal portions for further sealing the closure.

The clamping structure 102 is disposed adjacent the margins of the covering strips 100, 101, and includes a backing plate 104 at a face of the partition 85 and a flexible clamping member 105 at the other face of the partition. The backing plate 104 of suitable stiff material is adhered in position by a suitable adhesive material, and has a channel portion 104a for fitting snugly about the closing elements 72, 73, as shown in Fig. 19, and for providing backing support of the latter.

The flexible clamping member 105 of resilient rubber or other rubber-like material, molded and vulcanized to the form shown, has a hollow body portion 105a capable of enclosing the runner 83 and the pull-tab 83b and has flange portions 105b, 105c and 105d for seating against the wall of the partition 85. The flange portion 105c is, preferably, adhered to the margins 85a and 85b and to the closing elements 74 and 75 by a suitable adhesive material. The sidewalls of the hollow body portion 105a support the base por-

tions of the closing elements 74 and 75 as shown in Fig. 17, while a depending margin 105e opposite the flange portion 105c presses resiliently against the closing elements 74 and 75. This pressing action seals the opposing areas of the marginal portions of the closing elements 74 and 75 and presses the slide fastener 82a and 82b and the closing elements 72 and 73 against the backing plate 104 thereby sealing the closure at this region against leakage of fluid. A projecting portion 105f permits bending the flexible clamping member 105 at the flange portion 105c for opening and closing the sealing closure by the runner 83. A spring element 105g of steel, for example, may, if desired, be molded integral with the hollow body 105a for providing further pressing action of the depending margin 105e against the closing elements and slide fastener.

In the operation of the closure, the hollow body portion 105a is lifted and flexed about the flange portion 105c by manipulating the projecting portion 105f thus raising the depending margin 105e away from the closing elements 74 and 75. The slide fastener 82a and 82b is then engaged and the runner 83 is disposed within the hollow body portion, as shown in Fig. 16, after which the hollow body portion is returned to the position shown in the drawings thereby permitting the depending margin 105e to press against the closing elements and slide fastener as described hereinabove and sealing the end of the closure.

Fig. 4 illustrates an embodiment of the invention including adjacent margins 110 and 111 of flexible material, such, for example, as woven fabric, and a pair of closing elements 112 and 113 of resilient rubber or other rubber-like material or other suitable flexible material disposed at a face of the margins in overlapping relation to one another. Fastener means, such, for example, as a slide fastener 114, may be provided for detachably uniting the margins.

The closing elements 112 and 113 may be secured to the respective margins by an adhesive such as rubber cement, for example. Preferably, these elements 112 and 113 are molded and vulcanized integrally with the margins 110 and 111, the faces of the margins having a thin coating 110a and 110b, 111a and 111b of rubber.

Each closing element comprises a base portion 112a, 113a at a face of one of the margins 110, 111 and a laterally depending portion 112b, 113b terminating in a resilient marginal portion 115, 116 including a sealing surface 115a, 119, the marginal portion tapering to an edge 117, 118. The parts are constructed and arranged substantially in the manner described for the sealing closure shown in Figs. 1 and 1A, except that the laterally depending portion 113b has additionally a sealing surface 119 against which the edge 117 of the marginal portion 115 presses in sliding contact during engagement of the margins for providing a further seal by lip-action of the edge 117, while opposing areas adjacent the edges 117 and 118 are maintained in spaced-apart relation so that the lip-action of the edges will not be interfered with by engagement of adjacent surfaces. The sealing closure construction shown in Fig. 4 thus provides a double seal by virtue of the lip-action of the respective edges 117 and 118 in sliding contact with the respective sealing surfaces 115a and 119 of the closing elements, and it has been found that the seal is maintained during bending, inwardly or outwardly, of the

margins 110 and 111 and even to a large extent during twisting of these margins.

The sealing closure arrangement shown in Fig. 5 is especially useful for some conditions where greater flexibility of the laterally depending portions of the closing elements is desirable than that flexibility permitted by the constructions shown in Figs. 1 and 2, for example. In Fig. 5 a pair of closing elements 140 and 141 of resilient rubber or other rubber-like material are molded and vulcanized integral with and at a face of adjacent flexible margins 144 and 145 of woven fabric, for example. For increased flexibility, each closing element 140, 141 has a groove 142, 143 at the side adjacent a slide fastener 146 and at the junction of a base portion 140a, 141a and a laterally depending portion 140b, 141b for providing for a lesser wall thickness of the closing element at this region thereby facilitating flexure of the laterally depending portion during bending of the margin 144, 145 while maintaining adequate resilient pressure for initial sealing. Each laterally depending portion has a resilient marginal portion 147, 148 tapering to an edge 149, 150. The edge 150 of the closing element 141 is in sliding contact with a sealing surface 151 of the closing element 140 to provide a seal by lip-action of the edge 150 while opposing areas on the elements adjacent the edge 150 are maintained in spaced-apart relation so that lip-action of the edge will not be interfered with by engagement of adjacent surfaces. The marginal portion 147 of the element 140 may, if desired, be of lesser extent than that of the marginal portion 148 for preventing accidental damage to the marginal portion 147 by reason of the edge 149 becoming caught between the slide fastener elements during the engaging of the latter.

These and other variations may be made without departing from the scope of the invention as it is defined in the following claims.

I claim:

1. A sealing closure for adjacent margins, said closure comprising for said margins respectively a sealing surface and a closing element for overlapping said surface, said element having a marginal portion tapering to an edge for sealing by lip-action of said edge in contact with said surface while opposing areas on said surface and said element which trail said edge are maintained in spaced-apart relation.

2. A sealing closure for adjacent margins, said closure comprising a pair of elements for closing said margins by an overlapping relation of said elements, at least one of said elements having a flexible marginal portion tapering to an edge for contacting the other said element in sealing relation therewith by lip-action of said edge.

3. A sealing closure for adjacent margins, said closure comprising a pair of elements for closing said margins by an overlapping relation of said elements, each of said elements having a flexible marginal portion tapering to an edge for contacting the other of said elements in sealing relation therewith by lip-action of said edge.

4. A sealing closure for adjacent margins, said closure comprising a pair of elements for closing said margins by an overlapping relation of said elements, each of said elements having a flexible marginal portion tapering to an edge for sealing by lip-action of said edge in contact with the other of said elements while opposing areas on said elements adjacent the sealing edges are maintained in spaced-apart relation.

5. A sealing closure for adjacent margins, said

closure comprising a pair of elements for closing said margins by an overlapping relation of said elements, one of said elements having a sealing surface and the other of said elements having a resilient marginal portion tapering to an edge for sealing by lip-action of said edge in contact with said surface, the parts being constructed and arranged so that said marginal portion is resiliently held flexed against said surface while opposing areas on said elements adjacent said edge are maintained in spaced-apart relation.

6. A sealing closure for adjacent double-faced margins, said closure comprising at a face of the margins a pair of elements for closing said margins by an overlapping relation of said elements, a second pair of elements at the other face of said margins for closing the latter by an overlapping relation of the second pair of elements, at least one element of each said pair having a flexible marginal portion tapering to an edge for contacting the other said element in sealing relation therewith by lip-action of said edge.

7. A closure for sealing adjacent separable margins, said closure comprising fastener means for detachably uniting said margins, a pair of elements for closing the margins by an overlapping relation of said elements, one of said elements having a flexible marginal portion tapering to an edge for contacting the other element in sealing relation therewith by lip-action of said edge, and additional means for sealing an end of the closure.

8. A closure for sealing adjacent separable margins, said closure comprising slide fastener means including a runner for detachably uniting said margins, a pair of flexible elements for closing the margins by an overlapping relation of said elements, one of said elements having a resilient marginal portion tapering to an edge for sealing by lip-action of said edge in contact with the other said element, and means including a clamping structure for sealing an end of the closure, said structure having a depressed portion for housing said runner and having a depending margin for pressing said elements together in sealing relation at the region of the overlapping areas of said elements.

9. A sealing closure for adjacent separable margins, said closure comprising slide fastener means including a runner for detachably uniting said margins, a pair of flexible elements for closing the margins by an overlapping relation of said elements, one of said elements having a resilient marginal portion tapering to an edge for contacting the other said element in sealing relation therewith by lip-action of said edge, the parts being constructed and arranged so that said marginal portion is resiliently held flexed against the

other said element while opposing areas on said elements adjacent said edge are maintained in spaced-apart relation, said runner having a projecting member for manually manipulating the runner, said member extending through and between said elements at said opposing areas, and means including a clamping structure for sealing the end of the closure, said structure having a depressed portion for housing said runner and having a depending margin at each end of said depressed portion for pressing said elements together in sealing relation at the region of their overlapping areas.

10. A closure for sealing adjacent separable margins, said closure comprising fastener means for detachably uniting said margins, a pair of elements for closing the margins by an overlapping relation of said elements, one of said elements having a flexible marginal portion tapering to an edge for contacting the other element in sealing relation therewith by lip-action of said edge, and means for sealing an end of the closure, the sealing means comprising a clamping structure for pressing said elements together in sealing relation at the region of their overlapping areas.

11. A sealing closure for adjacent margins, said closure comprising a pair of elements for closing said margins by an overlapping relation of said elements, at least one of said elements having a marginal portion of elastic rubber-like material tapering to an edge for contacting the other said element in sealing relation therewith by lip-action of said edge.

12. A sealing closure for adjacent margins, said closure comprising slide fastener means for detachably uniting said margins, a sealing surface at one of said margins, and a closing element at the other margin, said element having a flexible marginal portion tapering to an edge for contacting said surface in sealing relation therewith by lip action of said edge.

13. A sealing closure for adjacent margins, said closure comprising slide fastener means for detachably uniting said margins, a pair of elements of elastic rubber-like material for closing said margins, said elements comprising supporting base portions and portions projecting laterally therefrom toward each other, at least one of the projecting portions tapering to an edge for contacting the other projecting portion in sealing relation therewith by lip-action of said edge, and said supporting base portions and projecting portions having a recess beneath the same for accommodation of said fastener means.

CARROLL P. KRUPP.
